(57) **CLAIM**

I claim the ornamental design for a rivet, as shown and described.

DESCRIPTION

FIG. 1 is a top plan view of a RIVET embodying my new design;

FIG. 2 is a front elevational view thereof;

FIG. 3 is a bottom plan view thereof;

FIG. 4 is a left side elevational view thereof;

FIG. 5 is a right side elevational view thereof;

FIG. 6 is a rear elevational view thereof;

FIG. 7 is a top, front, left perspective view thereof;

FIG. 8 is a top, front, right perspective view thereof;

FIG. 9 is a bottom, front, left perspective view thereof;

FIG. 10 is a bottom, front, right perspective view thereof;

FIG. 11 is a top plan view of a pusher embodying my new design;

FIG. 12 is a front elevational view of FIG. 11;

FIG. 13 is a bottom plan view FIG. 11;

FIG. 14 is a left side elevational view FIG. 11;

FIG. 15 is a right side elevational view FIG. 11;

FIG. 16 is a rear elevational view FIG. 11;

FIG. 17 is a top, front, left perspective view FIG. 11;

FIG. 18 is a top, front, right perspective view FIG. 11;

FIG. 19 is a bottom, front, left perspective view FIG. 11;

FIG. 20 is a bottom, front, right perspective view FIG. 11;

FIG. 21 is a top plan view of a receiver embodying my new design;

FIG. 22 is a front elevational view of FIG. 21;

FIG. 23 is a bottom plan view FIG. 21;

FIG. 24 is a left side elevational view FIG. 21;

FIG. 25 is a right side elevational view FIG. 21;

FIG. 26 is a rear elevational view FIG. 21;

FIG. 27 is a top, front, left perspective view FIG. 21;

FIG. 28 is a top, front, right perspective view FIG. 21;

FIG. 29 is a bottom, front, left perspective view FIG. 21; and,

FIG. 30 is a bottom, front, right perspective view FIG. 21.

The broken line showing of the surface is included for the

purpose of illustrating environment and forms no part of the

claimed design.

The elements of the claimed design are shown detached for

ease and clarity of illustration.
